UNITED STATES PATENT OFFICE.

WILLIAM M. BASHLIN, OF GROVE CITY, PENNSYLVANIA.

APPARATUS FOR TREATING WOOD.

1,198,990.

Specification of Letters Patent. Patented Sept. 19, 1916.

Application filed March 29, 1912. Serial No. 687,085.

To all whom it may concern:

Be it known that I, WILLIAM M. BASHLIN, a citizen of the United States, residing at Grove City, in the county of Mercer and State of Pennsylvania, have invented new and useful Improvements in Apparatus for Treating Wood, of which the following is a specification.

My present invention relates to improvements in the art of treating woods, and more especially to the extraction of turpentine and resins therefrom, and the primary object of the invention is to provide an improved apparatus whereby the treatment of the wood is rendered more rapid, uniform and effective, and an improved product is obtained. In the preferred embodiment of the invention, which is adapted for the extraction of turpentine and resins, the apparatus is so constructed that the body of wood to be treated is heated uniformly by the application of heat thereto both exteriorly and interiorly and also steam may be discharged into and distributed evenly throughout the body of the charge of wood to free the turpentine therefrom and to bring the resins to the surface of the chips or particles, and after the resins have been brought to the surface of the wood, chips or particles by the application of heat in the manner stated, a solvent is caused to flow through the charge to wash off the resins from the chips.

To these and other ends, the invention consists in certain improvements, and combinations and arrangements of parts, all as will be hereinafter more fully described the novel features being pointed out particularly in the claims at the end of the specification.

40 The accompanying drawing represents a central vertical section of an apparatus constructed in accordance with the present invention.

The construction shown is generally preferred, especially when the apparatus is employed for the purpose of extracting turpentine and resin from wood, but it will be understood that the invention is not necessarily limited to the particular construction shown, as modifications and changes may be made therein in adapting the invention to the conditions or requirements of each particular case, the scope of the invention being defined in the claims.

55 The apparatus shown in the present in-

stance embodies a retort which is composed of an inner shell 1 which is preferably cylindrical in form and is closed at top and bottom by suitable heads 2 and 3, one of these heads, the head 2 in the present instance, being preferably provided with a dome 4 which is covered by a tight-fitting lid 5, the latter being held in position by a suitable clamp 6. One side of the retort is also preferably provided with a manhole 65 7 which may be conveniently located toward the bottom of the retort and communicates with the interior thereof. This manhole is covered by a tight-fitting lid 8 which may also be held in position by a clamp 9. The 70 sides and bottom of the retort are inclosed by a jacket 10 which forms a heating space or chamber 11 which is adapted to receive steam from a pipe 12 which pipe may be connected to any suitable source of steam 75 supply such, for example, as the steam pipe 13. The bottom of the retort contains a support for the charge of wood and this support, according to the present invention, serves also as a filter or strainer. In the 80 present instance, the support embodies a suitable number of superposed plates 14 which are foraminous or formed with perforations 15, these perforations in the plates 85 being preferably staggered or offset, as shown.

A sheet of fabric 16 of appropriate character is preferably arranged at the under side of the uppermost foraminous plate and sheets of woven wire mesh 17 are interposed 90 between the middle plate and the top and bottom plates. This structure just described is suitably supported in the lower portion of the retort, for example, by an internal flange or ledge 18 and the plates and the mesh are maintained in proper spaced relation by suitable means such, for example, as the rings 19. A residuum chamber 20 is formed in the bottom of the retort below the support just described, and a pipe 21 is 95 100 provided for drawing off the residuum.

A pipe 21 connected to the pipe 21 may serve to initially introduce the solvent into the retort. The residuum chamber 20 contains piping which is preferably in the 105 form of a coil 22 having upwardly directed vents or orifices 23, this coil being connected by a pipe 24 to the steam supply pipe 13 whereby steam may be admitted to the coil 22 and this steam may be projected from 110

the vents or orifices 23 upwardly through the charge support and filter composed of the ports 14, 16 and 17. An outlet pipe 25 also extends through the bottom of the retort and 5 serves to withdraw the solvent or liquid therefrom, this outlet being shown provided with a perforated strainer head 26 and a blower 27 may be arranged in coöperative relation with the strainer head, the blower 10 being connected by a pipe 28 to the steam pipe 24, and steam may be admitted to the blower under the control of a valve 29 whereby the accumulation of any substance on the strainer head tending to clog the 15 perforations therein can be removed when necessary. The outlet pipe 25 for the solvent preferably leads to the inlet of a suitable circulating pump 30 and the discharge side of this pump is connected by a pipe 31 20 to the inlet pipe 32 of a coil or percolator 33, the coil shown in the present instance being formed with numerous downwardly directed vents or orifices 34 through which the solvent may be distributed evenly over 25 the charge contained in the retort.

That portion of the retort between the lower and upper coils 22 and 33 contains means for heating the interior of a charge or body of wood contained in the retort 30 whereby all portions of the charge may be heated uniformly by the application of heat both exteriorly and interiorly of the charge. Heating means of different kinds may be used for applying heat interiorly to the 35 charge. In the present instance, a closed helical heating coil 35 is shown and this coil may receive steam at an appropriate temperature through the pipes 36 and 37. These pipes may be conveniently connected 40 to the steam supply pipe 13 and provided with appropriate valves 38 and 39 whereby the steam supply to the coil and consequently the heating effect or temperature of the coil may be regulated as conditions 45 may require, the coil 35 and the pipes 36 and 37 forming a closed circuit with the steam supply pipe 13. Means is also provided for injecting steam in the body of the 50 charge for the purpose of liberating the turpentine and light oils therefrom. In the present instance, a suitable number of closed vertical manifolds 40 are shown which are connected in the form of a frame which surrounds the coil 35, and each manifold is 55 connected to a suitable number of steam distributing pipes 41, these pipes in the present instance radiating from the center of the retort and are provided with vents or orifices 42 through which the steam from 60 the respective manifolds is discharged and distributed uniformly within the body of the charge. The distributing pipes may also serve as means for distributing the solvent throughout the body of the charge and to 65 accomplish these results, a pipe 43 may be

used which leads to the manifolds 40, and this pipe is connected to and may receive steam from the supply pipe 13 under the control of a suitable valve 44. The pipe 43 is also connected to the solvent circulating 70 pump 30 and may receive solvent therefrom under the control of a valve 45. When the valve 45 is closed and the valve 44 is open, steam from the pipe 13 is admitted to the manifolds 40 and is discharged evenly 75 throughout the body of the charge through the perforated distributing pipes 41. By closing the steam valve 44 and opening the valve 45, the solvent may be caused to enter the manifolds 40 and discharge directly into 80 the mass through the distributing pipes. A pipe 46 leads from the dome 4 and is preferably connected to a suitable vacuum pump whereby a pressure below atmospheric pressure may be maintained within the retort 85 during the treatment of each charge for the extraction of the turpentine and resin. A pipe 47 also leads from the dome 4 and may serve to convey away to a condenser, the solvent remaining in the wood after the 90 solvent has been converted into gaseous form. The solvent in gaseous form may be withdrawn by any suitable exhaust device, a siphon or ejector 48 being shown in the present instance and the nozzle 49 therefrom 95 may receive steam from the steam pipe 13, as shown. In order to condense and thereby prevent high pressure of any gases that may accumulate in the upper portion of the retort, due to the combining of the gases 100 or hydrocarbons native to the wood with the hydrocarbons in the solvent, a closed cooling coil 50 may be used, that shown in the present instance being adapted to receive water or other cooling medium through the 105 inlet pipe 51 and the water from the coil may discharge through the outlet 52. Gage glasses 53 and 54 may be provided for indicating the levels of the liquid in the upper and lower portions of the retort, and a 110 safety valve 55 may be provided to prevent the development of excessive pressure in the retort.

Apparatus embodying the present invention may be operated in different ways, it 115 being understood that the invention is not restricted to any particular mode of using the apparatus.

I shall describe the preferred method of operating the apparatus for the purpose of 120 extracting turpentine and resin from wool, and it will be understood that this method is not restricted to the use of any particular solvent, although I prefer to employ a solvent composed of benzin and turpentine as 125 described in my co-pending application, Serial No. 659,634, a solvent of that character operating perfectly to dissolve the resin, the operation of extracting the resin may be performed at a relatively low temperature, 130

and the resin will be of a high grade. In operating the apparatus for the purpose stated, all valves are closed and the extractor or still is filled with chips of wood through the dome 4 whereupon the lid 5 is applied and tightened. Steam is then admitted to the jacket 11 and to the closed heating coil or medium 35 by opening the appropriate valves, and at the same time a vacuum pressure within the retort is produced by the vacuum pump connected to the pipe 46, the valve in the pipe 47 being at this time closed. The temperature within the retort is then raised almost to the boiling point of water, and steam is then slowly turned on into the perforated distributor 22 below the foraminous support for the charge as well as into the perforated distributing pipes 41 which are contained within the charge. The pressure of the steam may be varied according to whether the wood is fat or lean, and after the steam has been supplied in this manner for a few minutes, the degree of vacuum within the retort is then appropriately regulated. The steam should be turned on gradually and increased until the proper temperature is reached, and this temperature should then be maintained in order to insure a free and unchecked flow of the turpentine from the chips. Heating of the chips of the charge in this manner frees the chips of turpentine, and after the extraction of turpentine has been completed, steam to the lower perforated distributing coil 22 may then be cut off and the steam to the perforated distributing pipes 41 may also be cut off at this period. Steam continues to flow, however, to the outer jacket 11 and to the closed heating coil or medium 35, and the heat thus applied assists in removing any remaining vapors which are carried off by the vacuum. The heating effect is maintained and this heat acting upon the chips serves to draw out the resin in the wood, this action being facilitated owing to the substantially dry heat produced by the closed heating coil 35, with the result that the resin flows from the pores of the chips and accumulates on the surfaces thereof. With the heat at the proper temperature, the solvent is slowly turned on the top of the charge of chips, by discharging the solvent through the percolator or perforated coil 33. Preferably, the amount of heat applied is increased at this time in order to prevent the solvent from chilling the chips or hardening or setting the resin. After a sufficient quantity of solvent has been introduced into the extractor, through the pipe 21^a for example, the vacuum being maintained, cold water or other cooling medium is introduced into the coil 50 in the upper portion of the retort in order to avoid an unduly high temperature or the accumulation of gas at high pressure, as well as to condense any vaporized solvent

and cause it to drop upon the charge in the form of a liquid. The circulating pump 30 is then started, which causes the solvent to circulate through the charge, the pump producing a suction action at the bottom of the 70 retort which will draw the solvent through the charge, causing it to wash off the resin on the chips as well as causing the solvent to enter the wood and force the resin to the surface to be washed off by the solvent, this 75 circulation being repeated with the pump withdrawing the solvent from the bottom of the retort and returning it to the top thereof, the solvent being richly laden with resin which in turn acts as a solvent to assist in 80 removing more rapidly the resin remaining in the chips. After the solvent becomes heavy with resin, it may be transferred to and used in another retort or extractor, it being usual to employ a battery of retorts 85 which may be conveniently operated together. After the solvent has become very rich with resin and turpentine, it is introduced, as usual, into a still wherein the solvent and the turpentine and resin are separated in the well known manner by fractional distillation. By using a small amount of the solvent and causing it to circulate repeatedly through the mass of chips, a rich solvent is produced which acts quickly and 95 effectively and with a relatively small loss in distillation, economizing in the amount of fuel and steam used as well as saving time. The turpentine and resin having been extracted from the chips, there still remain 100 heavy high temperature and high gravity oils. In order to extract these oils, the wood is heated to a higher temperature and is subjected to a higher vacuum, and by producing another charge of solvent these oils 105 can be recovered. The chips freed from all the turpentine, oils and resins are in such condition that the cellulose is not destroyed or discolored and hence the chips may be used for paper pulp purposes.

In order to extract any solvent that may remain in the chips and thus avoid any loss of solvent, the steam supplied to the outer jacket and the interior heating coil or medium may be maintained, this causing the 115 solvent to be converted into a gas which can be removed from the extractor by the siphon or ejector 48 which operates to withdraw the solvent in gaseous form into the pipe 47 and said pipe conducts the gaseous solvent 120 into a suitable condenser. After most of the solvent has been removed from the chips in this way, the completion of the extraction of any remaining solvent may be produced by admitting steam to the retort 125 chamber through the perforated coil 22 and the perforated distributing pipes 41.

The apparatus shown is also capable of treating the wood chips to form a wood pulp. If it is desired to use the apparatus 130

for this purpose after the turpentine, oils, resin and solvent have been removed, the chips may remain in the retort or extractor and there treated with any of the well known pulping liquors such, for example, as by treating the wood first with either carbonate or bi-carbonate of soda which may be preliminary to the use of the caustic soda, sulfite or sulfate processes. A great economy in time and labor will be effected in this way owing to the fact that the amount of handling of the chips is reduced to a minimum and, moreover, a continuous and complete process serves to recover all the by-products and to reclaim the chips for further use. In using the apparatus for pulp making purposes, the pulping liquor may be pumped into the retort through the steam distributing pipes and thereby caused to act upon the entire body or charge of wood, and the circulating of the liquor will produce an intimate and quick chemical action. In treating the wood in this manner, a high pressure of steam in the jacket should be avoided in order that the pulp may have the natural color of the wood. Moreover, by using a low steam pressure and circulating the pulp liquor over and through the charge of wood, disintegration of the fiber into small pieces is avoided and, therefore, a product which is better in color and strength is obtained in less time and with less expense than is possible with the processes now generally practised. If, for any reason, heavy resins, tars or oils have not all been previously removed, these settle in the bottom of the retort under the perforated support and they may be then drawn off and refined through the outlet pipe 21. Any lighter by-products such, for example, as turpentine or lighter oils which may remain in the wood, will vaporize and may be recovered through the condensing pipe 47.

I claim as my invention:—

1. Apparatus for treating wood comprising a retort adapted to contain a charge of wood and having a jacket for heating such charge exteriorly, a closed steam heating coil arranged vertically and centrally within the retort for applying dry heat to the interior of the charge, and perforated distributing pipes grouped around said coil for introducing steam into the body of the charge of wood in the retort. 45

2. Apparatus for treating wood comprising a retort adapted to contain a charge of wood and having a jacket for heating such charge exteriorly, means arranged within the retort for applying dry heat to the interior of the charge, perforated distributing pipes arranged around said dry heating means, means for supplying steam to the distributing pipes, and means for supplying a solvent to the distributing pipes. 55

3. Apparatus for treating wood comprising a retort adapted to contain a charge of wood and having a jacket for heating such charge exteriorly, a closed steam heating coil arranged vertically and centrally within the retort for applying dry heat to the interior of the charge, manifolds arranged vertically and grouped about said coil, and perforated distributing pipes extending horizontally and radially from said manifolds. 65

In testimony whereof I have hereunto set my hand in presence of two subscribing witnesses. 70 75
